METHOD OF MAKING VENT VALVES FOR CONTAINERS

Ralph M. Berglund, Seattle, Wash., assignor to American Can Company, New York, N. Y., a corporation of New Jersey

Application August 23, 1944, Serial No. 550,744

3 Claims. (Cl. 18—59)

1

This invention relates to the manufacture of vent valves for can parts and has particular reference to molding a yieldable valve material in position on the perforated wall of a can to provide a vent valve container for food products.

The invention contemplates an improved simple molding process for producing a rubber or similar material yieldable valve for a can so that normally the valve closes a vent opening in the can. Some materials, such as cheese for example, require a ripening action and cheese may be sealed successfully in containers, provided the container is of a construction to allow for escape of gases created during the ripening process and provided the container prevents passage of air into the container. It is to the novel creation of a desired form of yieldable valve on a container wall that this invention is particularly directed.

An object of the invention is the provision of a method for making a vent valve by pressing a yieldable material such as rubber against a can end or other container part and to extrude a part of the rubber through one or more perforations in the container to secure the valve to the can end with thread or neck like connecting elements so that the body of the valve covers and seals a vent opening in the can, such a valve thereafter functioning to permit escape of generated gases from within the container.

Another object of the invention is the provision of a method of forming a valve in proper position relative to a vent opening in a can end by molding to the desired form and then heat treating the formed valve in a curing step to make it properly resistant and yieldable to internal pressures developed within the can in which the valved end is used.

A further object of the invention is the provision of a method of molding a yieldable valve in vent closing position for a can and subsequently subjecting the valve to a preloading step by means of which a predetermined yield point is established to the end that uniform valve action may be had.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a can end having a vent opening and adjacent perforations, this view illustrating one form of can end on which a vent valve may be created according to the method steps of the invention;

Fig. 2 is a similar view illustrating the can end after the application and formation of the vent

2

valve, parts being broken away and parts shown in section;

Fig. 3 is a sectional view drawn to an enlarged scale and showing principal parts of a preferred form of apparatus for extruding or molding a vent valve in position on a can end;

Fig. 4 is a sectional view similar to Fig. 3 but drawn to a smaller scale and illustrating a different form of apparatus for molding a vent valve onto a panel wall of a can end in a slightly different manner, parts being broken away;

Fig. 5 is a fragmentary sectional view on a reduced scale showing a typical drying machine converted to the heating of the molded vent valve formed on a can end so that by heat treatment the valve is cured and is conditioned for use;

Fig. 6 is a fragmentary sectional view drawn to the same scale as Fig. 4 and showing die members for reforming a portion of a can end with its applied vent valve as a preloading step for setting the pressure release point of the valve;

Fig. 7 is a perspective view of the upper portion of a can end with its applied completed valve.

As a preferred embodiment of the invention the drawings disclose can end parts and principal elements of apparatus for carrying out the steps of the present invention in which a vent valve A is molded in place in a can end or cover B. Such a can end preferably is provided with a central vent opening C formed in a raised central panel D. In the form illustrated in Fig. 1 perforations E surround the vent opening C and are preferably equally spaced in a concentric circle. This is exemplary of a can part suitable for receiving the vent valve A.

The first step in the present method of producing vent valves A comprises forcing a yieldable material such as rubber into position, preferably while heated, so that the vent valve is molded in place on the can end. In this formation of the valve, a domed disc F (Fig. 2) results from the application of the rubber to the exterior surface of the can end and this disc F covers over the vent opening C. Portions of the rubber are extruded through and completely fill the perforations E in the can end as connecting threads or necks G, these thread-like extrusions being merged on the opposite or interior side of the can end as an integral ring H.

As best illustrated in Fig. 3 the preferred form of molding apparatus comprises a valve disc molding block 10 and a valve ring molding block 11. One or both of these blocks may be movable relative to the other so that the blocks can be separated for positioning of a can end therebetween incident to the molding operation. A pilot boss 12 formed on the inner face of the block 11 provides for centralizing of the can end in the molding apparatus. It will be noted that the boss completely fills the vent opening C of the end. In

inserted position the inner face of the boss 12 is substantially flush with the outer wall of the located can end.

The block 10 has a disc forming mold cavity, recess or depression 13 sunk in its inner face and is shaped to provide for the disc F. The block 11 has an annular mold cavity, recess or depression 14 on its adjacent face, this depression being semi-circular in cross section and providing for the molded valve ring H.

Blocks 10 and 11 preferably are heated as this assists in the molding operation. Live steam as a heating medium has been found to be satisfactory and accordingly the mold blocks are constructed with such in mind. The block 10 is formed with a heating chamber 15 into which steam may be introduced from a supply pipe 16 connecting by a passageway or port 17 with the heating chamber. Steam is circulated through the block and from the chamber 15 it is discharged through a passageway or port 18 into a discharge pipe 19.

In a similar manner, block 11 may be steam heated. For this purpose a heating chamber 21 is formed in the block and steam is supplied by an inlet pipe 22 by way of a passageway or port 23. Steam from chamber 21 is discharged through a passageway or port 24 and thence through a discharge pipe 25. In this manner both mold blocks 10 and 11 may be maintained at the desired temperature, the type of rubber or other molding material determining the actual heat required.

When the blocks 10 and 11 are in closed position as in Fig. 3, with the inserted end B in place, rubber or the like confined within a supply well 28 formed in block 10, is forced through a port 29 into the mold cavity or recess 13. This may be done in any suitable manner as by means of a piston 31 secured to the lower end of an actuating rod 32.

As the heated rubber is forced through the port 29 into the molding recess 13 it completely fills the recess and an excess portion flows through the perforations E and into the valve ring mold recess 14 of the block 11. To insure that all of the spaces 13, 14 and perforations E be completely filled, a vent port 33 extends from the recess 14 in the block 11 to a vertically disposed vent passageway or port 34. Provision is also made for the passage of some rubber directly from the molding recess 13 through the boss 12 by means of a port 35 also connecting with the passageway 34.

After the molding step the block members 10, 11 are separated and the can end B with its attached vent valve A is removed from the mold. Owing to the small diameter of the ports 29, 33 and 35 any extruded rubber confined in the ports will be broken off as the valve A is taken out of the mold.

The description of molding a vent valve in place on a can end thus far has contemplated forming the valve from semi-liquid or jellied rubber. In Fig. 4 there is disclosed an apparatus for effecting a slightly different molding step. The apparatus of this modified form comprises a valve disc molding block 48 and a valve ring molding block 49. The molding blocks may be movable relative to each other the block 48 being movable as shown in the drawing. A can end B is placed between the molding blocks. A rod 50 disposed in the block 49 provides a support for the can end, its inner end being inserted in the vent opening C of the can end.

The inner face of mold block 48 is recessed as a disc shaped mold 51 to accommodate or pro-

vide for the domed valve disc F. In like manner the inner face of the mold block 49 has a mold recess 52 providing for the molded valve ring H. The movable molding block 48 is mounted in a movable sleeve 53. According to this modified molding step as effected in the apparatus shown in Fig. 4, a preformed disc P of rubber or other suitable material is used instead of the jellied rubber. This rubber disc is inserted between the can end B, on its rod 50, and the inner face of the movable block 48. The disc P is lightly held in the recessed end of the block by sliding of the rod 50 forward (toward the left, Fig. 4) to engage the disc. With the rubber disc P in inserted position, the sleeve 53 is moved toward the block 49 until its inner face engages against the can end B held in the block. This fully confines the rubber disc P within the mold parts. The block 48 then is moved toward the right for the molding operation.

Provision is made for heating both of the molding blocks 48, 49. For this purpose an inner chamber 54 is formed in the block 48. Live steam or other suitable heating media is circulated into and through the chamber by means of an inlet pipe 55 and a connecting passageway leading into the chamber and by a passageway to a discharge pipe 56 leading from the chamber.

In a similar manner the block 49 is provided with a heating chamber 57, live steam being introduced into the chamber by way of an inlet pipe 58 and a connecting passageway, the steam escaping through a passageway and into a discharge pipe 59. The sleeve 53 is slotted as shown to allow for clearance of the pipes 55, 56 during movement of the block 48.

To insure complete filling of the molds during the transformation of the disc P into a valve A, a port 60 is formed in the block 49. This port 40 communicates with the groove or mold recess 52 and also connects with a vent passageway or port 61. The excess of rubber contained in the disc P over that needed for molding the valve A is forced into the channels 60, 61 as in the instance of the former described die parts of Fig. 3. Thus it will be seen that the same vent valve A is produced regardless of whether the apparatus of Fig. 3 or the modified apparatus of Fig. 4 is used.

For most purposes the molded valve A is only in a raw condition and further curing of the rubber is desirable. This curing of the valve is best effected in a heating and drying operation which may be performed in a typical can end drying apparatus. Fig. 5 illustrates a portion of the principal parts of such an apparatus which is more fully described in the Horace J. Paynter United States Patent 1,754,483, issued April 15, 1930. Such an apparatus includes a chain conveyor 65 having spaced feed dogs 66 on which the can ends B with their molded valves A may be placed for advancement into the drying apparatus. Such a conveyor places each can end into a rotary can end conveyor or feeding device 67.

Such a conveyor rotates within a heat insulated housing 68 enclosing a drying chamber 69. The drying chamber may be maintained at a substantially uniform temperature for the proper curing of the vent valves. This may be done with heated air and is similar to the drying of lined can ends as in the manner fully described in the aforesaid Paynter patent. It is during relatively slow passage of the can ends within the drying chamber that the vent valves A are fully cured and conditioned for proper operations. The cured valve 70 can end or cover units after passage through the

drying chamber are discharged as illustrated in Fig. 5 onto a discharge conveyor 70, a platform or other suitable place of deposit for further treatment.

As previously mentioned, it is desirable in order to provide for uniform valve action to preload or set up a certain tension within the valve so that it will react to a definite pressure. Fig. 6 illustrates a preferred embodiment of reforming devices for preloading the cured valve on its can end B in a reforming action. In this disclosure die parts are used to form a ridge K in the can end B surrounding its vent opening C. This is for the purpose of placing the desired tension on the rubber valve. Obviously the same preloading effect could be obtained by other reforming of the can end. For example, the vent opening surrounding edge could be reformed into a flange as by a spinning action.

In Fig. 6 is shown a die mechanism which includes an upper die member 75 and a lower die member 76. The lower die member is provided with a circular or annular projection or ridge 77. The upper die member 75 is formed with a concave pocket or recess 78 the walls of which closely conform to the shape of the domed disc F of the valve.

The can end B is inserted between the die members 75, 76 and preloading of the can end is brought about by a closing of the die members. The resulting annular ridge K is formed in the panel D of the can end, at this time the upper die member backing up and preserving the disc-shaped portion F of the valve. By means of this simple reforming step the valve is preloaded or conditioned for use. The fully formed and preloaded vent valve cover or can end is now in condition for attachment to a can body. This may be done in the usual manner as by seaming the can end onto a can body.

It is thought that the invention and many of its attendant advantages will be understood from the foregoing description, and it will be apparent that various changes may be made in the steps of the process described and their order of accomplishment without departing from the spirit and scope of the invention or sacrificing all of its material advantages, the process hereinbefore described being merely a preferred embodiment thereof.

I claim:

1. The method of molding and securing a member composed of yieldable material in position on opposite sides of a perforated can part having a vent opening therein to form a vent valve therefore, comprising interposing said can part between die members having opposed recesses therein communicating through the perforation in the can part, said recesses together corresponding in shape to the configuration of the completed vent valve, then forcing a yieldable extrudable material against said can part to fill the recess in one die member and thence through the can part perforation into the recess of the other die member to fill the recess therein and thus complete the molded formation of the valve member on opposite sides of the can part to cover the vent opening in the latter, heating said die members during the described operations to facilitate the molding into shape and securing of the valve member to the can part, and then conditioning said member by deforming the can part adjacent the vent opening so that the valve member will yield under a predetermined gas pressure to permit escape of such gas through the can end vent 75

opening after said end has been secured to a can body filled with a gas generating product.

2. The method of molding and securing a member composed of yieldable material in position on opposite sides of a can end having a centrally disposed vent opening therein and a plurality of spaced perforations surrounding said vent opening to form a vent valve for said opening, said method comprising interposing said can end between die members having opposed recesses there-in communicating through said spaced perforations of the can end, said recesses together corresponding in shape to the configuration of the completed vent valve, then forcing a yieldable extrudable material against said can end to fill the recess in one die member and thence through the can end perforations into the recess of the other die member to fill the recess therein and thus complete the molded formation of the valve member on opposite sides of the can end to cover the vent opening therein, heating said die members during the described operations to facilitate the molding into shape and securing of the valve member to the can end, and then conditioning said valve by deforming the can end adjacent the vent opening so that the valve member will yield under a predetermined gas pressure to permit escape of such gas through said vent opening after the can end has been secured to a can body filled with a gas generating product.

3. The method of molding and securing a member composed of yieldable material in position on opposite sides of a can end having a centrally disposed vent opening therein and a plurality of circumferentially spaced perforations surrounding said vent opening to form a vent valve for said opening, said method comprising placing a pre-formed disc of yieldable extrudable material within in a recess in one of a pair of recessed die members, interposing said can end between said die members with the die member recesses in communication through the perforations of the can end, said recesses together corresponding in shape to the configuration of the completed vent valve, then forcing said die members together to compress said disc against the can end to fill the recess in one die member and thereafter to extrude portions of the compressed disc material through the can end perforations into the recess of the other die member to fill the latter recess and thus complete the molded formation of the valve member on opposite sides of the can end to cover the vent opening therein, heating said die members during the described operations to facilitate the molding into shape and securing of the valve member to the can end, and finally conditioning said valve member by deforming the can end adjacent the vent opening so that the valve member will yield under a predetermined gas pressure to permit escape of such gas through the can end vent opening after said end has been secured to a can body filled with a gas generating product.
